UNITED STATES PATENT OFFICE.

CHARLES P. TATRO AND GEORGE DELIUS, OF SEATTLE, WASHINGTON.

PROTECTING PILING FROM TEREDOS AND THE LIKE.

Application filed March 21, 1921, Serial No. 454,165. Renewed September 26, 1923.

To all whom it may concern:

Be it known that we, CHARLES P. TATRO and GEORGE DELIUS, citizens of the United States of America, and residents of the city 5 of Seattle, in the county of King and State of Washington, have invented certain new and useful Improvements in Protecting Piling from Teredos and the like, of which the following is a specification.

10 Our invention relates to a process for protecting wooden piling from the attacks of teredo and other wood borers. The present application is an improvement upon our Patent No. 948,355.

15 The object of our present invention is to produce a process for the purpose described which is more efficient, particularly in chlorine generation, than that of our previous patent, and to produce a process by 20 the use of which a large part of the rather cumbersome and expensive apparatus is eliminated.

Our invention comprises those novel steps 25 which are described in the following specification and particularly defined by the claims terminating the same, one form of apparatus for carrying out the process being shown in the accompanying drawings.

The drawings illustrate a series of piles 30 supporting a wharf, and a form of apparatus in connection therewith which may be used in carrying out our process.

In our patent referred to above, two electrolytic terminals, a cathode and an anode, 35 are placed adjacent a pile to be protected, and current is then passed through the circuit, the sea-water forming the electrolyte. In this connection it should be noted that the teredo is one of a series of salt water 40 molluscs and does not exist in fresh water. Thus, whenever it is desired to use our process for protecting wooden piling or other structure against teredo, it is always possible to utilize the water in which the piles 45 stand as an electrolyte.

Our former apparatus, while effective, was not as efficient as it might have been. The cathode and anode were both submerged 50 adjacent each other and adjacent the pile to be protected. This required a double series of electric leads, positive and negative, for each pile to be protected. Further, as sea-water is decomposed by electrolysis, chlorine is liberated at the anode 55 and sodium hydroxide and hydrogen are

formed at the cathode. The hydroxide and chlorine, having a strong affinity one for the other, will, when in such close proximity, react one upon the other with the result that a large portion of the chlorine 60 is lost in the formation of hypochlorites, which were of little value in protecting the piling against teredo.

Sea-water is of relatively high conductivity, and its resistance is so slight as to 65 be measured only with the most delicate instruments. It is possible, therefore, to pass a relatively weak current through sea-water to a great distance. This fact we utilize in our improved process, placing the cathode 70 at a distance from the anode. Preferably we employ a single cathode and a large number of anodes. Thus one anode may be placed adjacent each pile to be protected and the single cathode, being placed at a distance, 75 serves for the entire series of anodes.

By the arrangement described, the chlorine which is liberated at the anodes is removed from the sodium hydroxide formed 80 at the cathode. This obviates the formation of hypochlorites and assures the maximum efficiency from the chlorine generated. No chlorine is lost by this method except such as may be absorbed or dissolved in 85 the water immediately surrounding it. This chlorine water, however, comes in contact with the piles and is as effective as the chlorine in destroying teredo, especially as its tendency is to sink to the foot of the pile, on account of its specific gravity being 90 higher than the sea-water.

The preferred arrangement of the apparatus which is illustrated in the drawing contemplates the wrapping about each pile of a flexible insulated conductor 1 having 95 thereon a plurality of terminal balls 2, which are electrically connected to the flexible conductor. These are spaced at intervals upon the conductor 1, and are of material which is insoluble and non-corrosive 100 by the chlorine liberated. Carbon in the form of graphite is a suitable material for such balls. The flexible conductor, carrying the balls, may be wrapped about the pile 3 as many times as desired and the coils so formed may be closer or farther apart as the circumstances may require. The cathode 5 is placed at a distance from any of the anodes, as explained above, and 105 may be, as shown here, a sheet of conduct- 110

ing material, such as iron. Other arrangements and apparatus may be found desirable to suit varying conditions.

As current is turned on in the circuit, 6 chlorine is liberated from each of the balls 2. These are in intimate contact with the pile 3 and the chlorine generated is brought into contact with the pile. The gaseous chlorine rises along the pile and the chlorine 10 water sinks. Thus the pile is swept upward and downward with nascent chlorine. The teredo always lies in his bore with two feelers and feed tubes exposed and reaching into the water for sustenance. When 15 the nascent chlorine or chlorine water comes in contact with these feelers and feed tubes, the teredo is destroyed thereby. The effect is in no sense electrical, but is rather due to the destructive effect of the chlorine.

20 In this process the current employed should always be direct current and the direction thereof should never be reversed, nor should the cathode be brought close to any one of the anodes, for it is our desire to generate only chlorine at the anodes.

25 Any generation of a hydroxide at or near the anodes, such as would occur if the current were reversed, or if the electrodes were close to each other, would neutralize the 30 chlorine generated, and so render the process less effective, as was the case in our former process, where the two terminals were adjacent one to the other.

We prefer to employ metallic cathode.

35 Now, if the current were reversed, the carbon anodes would become the cathodes generating hydrogen and sodium hydroxide, and the metal cathode would become the anode. No chlorine would then be formed, 40 but rather the chloride of the metal which composed the new anode. This would have no effect in destroying the teredo or other borers.

What we claim as our invention is:

45 1. The process of protecting wooden pil-

ing in salt water from teredo and the like which consists in placing an anode in the water adjacent the pile, in placing a cathode in the water at a distant point, and in passing a direct current through these 50 terminals, the circuit being completed through the water.

2. The process of protecting wooden pil- 55 ing in salt water from teredo and the like which consists in placing an anode which is insoluble and not chemically affected by chlorine in the water adjacent the pile to be protected, in placing a cathode in the water at a distant point, and in passing a 60 direct current through these terminals, the water forming the electrolyte.

3. The process of protecting wooden pil- 65 ing in salt water from teredo and the like which consists in placing an anode in the water in intimate juxtaposition to the pile, in placing a cathode in the water at a distant point, and in passing a direct current through these terminals, the circuit being completed through the water.

4. The process of protecting wooden pil- 70 ing in salt water from teredo and the like, which consists in wrapping an elongated, substantially continuous insoluble anode about the pile, in placing a cathode in the water at a distant point, and in passing a 75 direct current through said terminals, the circuit being completed through the water.

5. The process of protecting a series of spaced wooden piles in salt water from 80 teredo and the like, which consists in placing an anode in the water adjacent each pile, in placing a single common cathode in the water at a distant point, and in passing a direct current through said terminals, the water forming the electrolyte.

85 Signed at Seattle, King County, Washington, this 15th day of March, 1921.

CHARLES P. TATRO.
GEORGE DELIUS.
